DRIVING DEVICE

Sydney Zonis, Bridgeport, Conn., assignor to The
Singer Manufacturing Company, Elizabeth,
N. J., a corporation of New Jersey

Application September 17, 1943, Serial No. 502,742

8 Claims. (Cl. 74—243)

1

This invention relates to driving devices of the pulley and belt type, and more particularly to the type including belts provided with a series of cleats, clips or the like spaced uniformly from each other lengthwise of the belt. A cleat-belt of this type is disclosed, for example, in the United States patent of A. Steward, No. 667,830, Feb. 12, 1901.

Cleat-belts have been used extensively in connection with sewing machines; the employment of belts having spaced individual cleats or cleat-clusters being dependent upon the driving load imposed upon the belts. For example, in the United States patent of F. Parry, No. 2,314,513, Mar. 23, 1943, pulleys carried by the bracket-arm and bed shafts of a sewing machine are illustrated as connected by a belt having spaced triple-cleat clusters, while the pulley of a rotary take-up shaft of the machine is shown as connected to another pulley of the arm-shaft by a belt having spaced individual cleats. In prior constructions of this character, it has been necessary to employ at least four pulleys subject to rapid acceleration and deceleration in starting and stopping operation of the machine.

The present invention has for an object to reduce the inertia of the operating mechanism of a machine, thereby to facilitate acceleration and deceleration of the operating mechanism.

Another object of the invention is to provide a combination pulley which is compact, of relatively low cost of manufacture and which lends itself readily to the application of cleat-belts thereto.

Other and more specific objects of the invention will be apparent from the following description and claims.

The invention consists in the structural features of the combination pulley and associated cleat-belts hereinafter described in connection with the accompanying drawing, which illustrates a preferred embodiment of the invention and in which:

Fig. 1 represents a vertical section of the bracket-arm standard of a sewing machine containing the improved pulley and the belt connections therewith. Fig. 2 represents an enlarged vertical section of the arm and bed shaft pulleys, with the connecting cluster-cleat belt partly broken away. Fig. 3 shows the arm-shaft pulley and a portion of the individual-cleat belt in side elevation, as viewed from the side opposite that shown in Fig. 1. Fig. 4 represents a perspective view of the improved combination pulley.

Referring to the drawing, the sewing machine

2

shown has a frame including a bed-plate 1 from which rises the hollow standard 2 of a bracket-arm 3. Extending rearwardly from the upper portion of standard 2 is a recessed cover-plate 4.

Suitably journaled in the bracket-arm 3 is a rotary driving or arm-shaft 5, and rotatably journaled at the under side of the bed-plate 1 is a driven or bed-shaft 6 disposed substantially parallel to the arm or driving shaft 5. A third shaft 7 is rotatably disposed within the cover-plate 4, substantially at the level of and parallel to the arm-shaft 5. It will be obvious that either the arm-shaft 5 or the bed-shaft 6 may be employed as the driving shaft.

Secured by a screw 8 upon the arm-shaft 5 is a hub 9 of a belt-pulley 10; said hub 9 having a shaft-opening 11. One end of the pulley-hub 9 has a radial flange 12 integral with or carrying a cylindrical rim 13 of the pulley. The hub-flange 12 preferably merges into or is connected to the pulley-rim 13 substantially medianly of the width of the pulley-rim, whereby a portion of the pulley-rim extends from one side of the flange 12 to overhang the hub 9 and another portion of the rim 13 extends from the opposite side of the flange 12 to overhang the arm-shaft 5 adjacent the hub 9.

The outer face of the pulley-rim 13 is provided with a plurality of narrow grooves 14 which alternate circumferentially of the rim 13 with a plurality of relatively wide grooves 15 also provided in said face; said grooves 14 and 15 extending widthwise of the pulley-rim 13 and being open at the opposite side edges of said pulley-rim. The outer face of the pulley-rim 13 is additionally provided substantially medianly of the width of said rim with a circumferential groove 16. Seated in the circumferential groove 16 is a belt-separating member in the form of a wire-ring 17 intersecting the grooves 14 and 15.

The bed-shaft 6 carries a belt-pulley 18 of substantially the same size as the pulley 10 and having an external hub 19 secured by screws 20 upon the shaft 6. The belt-pulley 18 additionally has an internal hub 21 embracing the shaft 6. Between the hub-portions 19 and 21 is a radial hub-flange 22 carrying and preferably integral with one end of a pulley-rim 23 which overhangs the internal hub 21.

The outer face of the pulley-rim 23 is provided with a series of belt-cleat receiving grooves 24 of substantially the same width as the wide grooves 15 of the belt-pulley 10. The grooves 24 preferably extend throughout the width of the pulley-rim 23 and are spaced from each other,

circumferentially of the rim 23, to correspond to the circumferential spacing of the wide grooves 15 of the belt-pulley 10. The outer face of the pulley-rim 23 is also provided adjacent one edge of the rim with a circumferential groove 25 receiving a belt-guard wire-ring 26. The wire-ring 17 of the pulley 10 and the wire-ring 26 of the pulley 18 are preferably disposed in a common plane.

The third shaft 7 carries a belt-pulley 27 which, in the present instance, is one half the size of the pulleys 10 and 18. The belt-pulley 27 is provided in its outer face with a plurality of belt-cleat receiving grooves 28 which extend transversely of the face of the pulley 27 and correspond in width to that of the narrow grooves 14 of the belt-pulley 10. The belt-pulley 27 is aligned with the portion of the pulley 10 at the left hand side of the belt-separating ring 17, while the belt-pulley 18 is aligned with the portion of the pulley 10 at the right hand side of said ring 17.

Engaging the belt-pulleys 10 and 27 is a cord-belt 29 provided with a series of individual cleats 30 which extend transversely and are evenly spaced from each other lengthwise of the belt. The belt-cleats 30 protrude from the pulley-engaging face of the belt 29 and enter the pulley-grooves 28 which are proportioned to insure against slippage of the belt upon the pulley. As illustrated in Fig. 3 of the drawings, the cleats 30 of the belt 29 also enter both the narrow grooves 14 and the wide grooves 15 of the belt-pulley 10 at the left hand side of the belt-separating ring 17. The narrow grooves 14 of the pulley 10 are proportioned correspondingly to the grooves 28 of the pulley 27, thereby also to insure against slippage of the belt 29 upon the pulley 10. The wide grooves 15 of the pulley 10 provide clearance for the belt-cleats 30 disposed between the cleats which engage the narrow grooves 14.

Engaging the pulleys 10 and 18 is another cord-belt 31 provided with a series of triple-cleat clusters 32 which are evenly spaced from each other lengthwise of the belt 31; the cleat-clusters 32 protruding from the pulley-engaging face of the belt 31 and being more widely spaced from each other than are the individual cleats 30 of the belt 29. The cleat-clusters 32 each preferably comprise three individual cleats in contact with each other, but it will be obvious that a single, correspondingly wide cleat or a different number of cleats may be employed.

The cleat-clusters 32 of the belt 31 enter the successive wide grooves 15 of the pulley 10 at the right hand side of the ring 17 and with sufficient snugness to prevent slippage of the belt 31 upon said pulley; the belt-portions between the cleat-clusters 32 extending across the narrow grooves 14 of the pulley 10. The cleat-clusters 32 of the belt 31 also enter the grooves 24 of the bed-shaft pulley 18 to insure against slippage of the belt 31 upon that pulley.

The cord-belts 29 and 31 each comprise adjacent coils of cords; the cords of the two belts being of opposite twists selected so that said belts both tend to creep toward the belt-separating ring 17 of the pulley 10. This arrangement eliminates any necessity for employing additional belt-guard rings which would add to the inertia of the driving mechanism. Furthermore, this arrangement leaves the grooves open at the opposite ends thereof, whereby the two belts 29 and 31 may be more conveniently applied to the pulley 10. Similarly, only one guard ring need be employed in connection with the belt-pulley 18. The belt

29 in the present instance is so short that no guard-ring need be employed in connection therewith, the guard-ring 17 of the pulley 10 being sufficient to hold the belt 29 upon the pulley 27.

5 By extending both the narrow grooves 14 and the wide grooves 15 of the pulley 10 across the entire widthwise face of said pulley, the pulley may be more readily manufactured, thereby reducing the cost thereof. Furthermore, the pulley 10 metal thus additionally removed substantially decreases the weight of the pulley. The described combination pulley therefore has the advantages of compactness, lightness in weight and low manufacturing cost.

15 Having thus set forth the nature of the invention, what I claim herein is:

1. A driving member comprising a cleat-belt pulley having a cylindrical rim provided in the outer face thereof with a plurality of relatively narrow and wide belt-cleat receiving grooves successively alternating circumferentially and each extending widthwise across the entire belt face of said rim, and a belt-separating member extending circumferentially and disposed medianly of said face of the rim.

20 2. A driving member comprising a cleat-belt pulley having a cylindrical rim provided in the outer face thereof with a plurality of relatively narrow and wide belt-cleat receiving grooves successively alternating circumferentially and each extending widthwise across the entire belt face of said rim, said grooves being open at the opposite ends thereof, and belt-separating means disposed medianly of said face of the rim.

25 3. A driving member comprising a cleat-belt pulley having a cylindrical rim provided in the outer face thereof with a plurality of relatively narrow and wide belt-cleat receiving grooves successively alternating circumferentially and each extending widthwise across the entire belt face of said rim, said face being additionally provided substantially medianly of the width thereof with a circumferential groove, and a belt-separating ring seated in said groove.

40 4. A driving member comprising a cleat-belt pulley having a hub provided with a shaft-opening and with a flange extending radially from one end of the hub, a cylindrical rim carried by and widthwise extending in opposite directions from said flange, said rim being provided in the outer face thereof with a plurality of relatively narrow and wide belt-cleat receiving grooves successively alternating circumferentially and each extending widthwise across the entire belt face of said rim, and belt-separating means disposed upon the outer face of said rim.

45 5. A driving member comprising a cleat-belt pulley having a hub provided with a shaft-opening and with a flange extending radially from one end of the hub, a cylindrical rim carried by said hub medianly of the width of said rim, said rim being provided in the outer face thereof with a plurality of relatively narrow and wide belt-cleat receiving grooves successively alternating circumferentially and each extending widthwise across the entire belt face of said rim, and a belt-separating member disposed medianly of said face of the rim.

60 6. A driving device comprising a driving shaft, a pair of driven shafts, a cleat-belt pulley mounted upon said driving shaft and having a cylindrical rim provided in the outer face thereof with a plurality of relatively narrow and wide belt-cleat receiving grooves alternating circumferentially of said rim, a second cleat-belt pulley

mounted upon one of said driven shafts and having a cylindrical rim provided with narrow cleat-receiving grooves corresponding in spacing and width to the narrow grooves of said first pulley, a cleat-belt connecting said two pulleys and having cleats spaced from each other lengthwise of the belt at a distance equal to the groove spacing of said second pulley, a third cleat-belt pulley mounted upon the other of said driven shafts and having a cylindrical rim provided with wide cleat-receiving grooves corresponding in spacing and width to the wide grooves of said first pulley, and a cleat-belt connecting said first and third pulleys and having cleats spaced from each other lengthwise of the belt at a distance equal to the groove spacing of said third pulley.

7. In a driving device having a driving shaft, a pair of driven shafts, a cleat-belt pulley mounted upon one of said driven shafts and having a cylindrical rim provided in the outer face thereof with a plurality of relatively narrow cleat-receiving grooves, a cleat-belt operatively connecting said driving and the first mentioned driven shaft, said cleat-belt having cleats spaced from each other lengthwise of the belt at a distance equal to the groove spacing of said pulley, a second cleat-belt pulley mounted upon the other of said driven shafts and having a cylindrical rim provided with relatively wide cleat-receiving grooves each being circumferentially spaced from the other at a distance twice that distance between the grooves of the first mentioned pulley, and a second cleat-belt operatively connecting said driving and the second mentioned driven shaft, said second cleat-belt having cleats spaced from each other lengthwise of the belt at a distance equal to the groove spacing of said second pulley; the improvement which comprises a third cleat-belt pulley mounted upon said driving shaft and having a hub provided with a shaft-opening and with a flange extending radially from the hub, a cylindrical rim carried by said flange and being provided in the outer face thereof with a plurality of relatively narrow and wide cleat-receiving grooves successively alternating circumferentially and extending widthwise across the entire belt face of said rim, said narrow and wide grooves corresponding in spacing and width with the re-

spective grooves of said first and second pulleys, said belts embracing said third pulley in adjacent relation to each other, and a belt-separating member disposed between said belts and medianly of said face of the rim.

8. In a driving device having a driving shaft, a pair of driven shafts, a cleat-belt pulley mounted upon one of said driven shafts and having a cylindrical rim provided in the outer face thereof with a plurality of relatively narrow cleat-receiving grooves, a cleat-belt operatively connecting said pulley with said driving shaft, said belt having cleats whose width lengthwise of the belt and whose spacing between cleats are equal substantially to the pulley groove width and the pulley groove spacing respectively, a second cleat-belt pulley mounted upon the other of said driven shafts and having a cylindrical rim provided with relatively wide cleat-receiving grooves each being circumferentially spaced from the other at a distance twice that distance between the grooves of the first mentioned pulley, and a second cleat-belt operatively connecting said second pulley with said driving shaft, said second belt having cleats whose width lengthwise of the belt and whose spacing between cleats are equal substantially to the groove width and groove spacing respectively of said second pulley; the improvement which comprises a third cleat-belt pulley mounted upon said driving shaft and having a hub provided with a shaft-opening and with a flange extending radially from the hub, a cylindrical rim carried by and widthwise extending in opposite directions from said flange, said rim being provided in the outer face thereof with a plurality of relatively narrow and wide belt-cleat receiving grooves successively alternating circumferentially and extending widthwise across the entire belt face of said rim, said narrow and wide grooves corresponding in spacing and width with the respective grooves of said first and second pulleys, said rim being additionally provided substantially medianly of the width thereof with a circumferential groove, and a belt-separating ring seated in said groove, said belts embracing said third pulley in adjacent relation to each other, with one belt disposed on either side of said ring.

SYDNEY ZONIS.
